United States Patent Office

Des. 183,944
Patented Nov. 18, 1958

183,944

FRONT FOR A WALL OVEN

William J. Miller, Elmo E. Aylor, and
Armour H. Titus, Jr., Galesburg, Ill.

Application December 2, 1955, Serial No. 39,132

Term of patent 14 years

(Cl. D81—25)

Fig. 1 is a front elevational view of the wall oven embodying our new design;

Fig. 2 is a sectional view taken on lines 2—2 of Fig. 1, looking in the direction of the arrows; and,

Fig. 3 is a sectional view taken on the lines 3—3 of Fig. 1, looking in the direction of the arrows.

We claim:

The ornamental design for a front for a wall oven, as shown.
